DISPENSING CONTAINER FOR TOOTHPICKS
OR OTHER SIMILAR ARTICLES

Albert H. Repp, Johnstown, Pa.

Application November 20, 1930
Serial No. 496,975

3 Claims. (Cl. 312—73)

My invention relates to improvements in receptacles, particularly adapted for dispensing tooth-picks, soda-straws, matches, cigarettes and the like.

5 The primary object of the invention is to provide a receptacle in which the articles to be dispensed may be easily packed by the manufacturer for sale and then used by the consumer for dispensing the articles to the individual user, in a 10 sanitary, self-serving manner, without the necessity of further handling the articles.

A further object of the invention is to provide a receptacle having openings through which the articles are dispensed, the bottom of the receptacle 15 being designed to automatically cause the articles to be successively projected through and beyond the openings, whereby the articles may be conveniently grasped and extracted from the receptacle.

20 Another object of the invention is to provide an article of the above-mentioned character which is simple and durable in construction, efficient in performing its function and inexpensive to manufacture.

25 Other objects and advantages of the invention will be apparent during the course of the following description.

In the accompanying drawing, forming a part of this specification and in which like numerals 30 are employed to designate like parts throughout the same,

Fig. 1 is a perspective view of the receptacle,
Fig. 2 is a longitudinal sectional view of the same,

35 Fig. 3 is a horizontal sectional view,

Fig. 4 is a fragmentary perspective view, showing more clearly the formation of the bottom, and,

Fig. 5 is a perspective view of the cover for the receptacle.

40 In the drawing, wherein for the purpose of illustration, I have shown a preferred embodiment of my invention, the numeral 5, denotes generally, the body of the receptacle, which is preferably constructed of card-board, and is substantially 45 rhombic in shape, as shown more clearly in Fig. 3. The body is provided with a top 10, and an inverted pyramidal shaped bottom 9, having its apex disposed in the center of the body. A depending skirt 11, surrounds the lower end of the 50 body and extends below the apex of the bottom to support the receptacle in a vertical position. A vertical partition 8 is disposed axially of the body 5 and extends between the two corners of the body nearest its vertical axis, dividing the body 55 into compartments. The two corners farthest

from the axis of the body are perforated on opposite sides, as at 12, adjacent their upper ends, and by removal of the perforated portions, elongated vertical slots or openings 7, are formed, through which the tooth-picks 13, or other articles are dispensed.

The receptacle may bear advertising matter of the manufacturer on its sides, and in order that the advertising matter may be concealed when the receptacle is used by the consumer for dispensing the articles, I provide an ornamental cover 14, as fully shown in Fig. 5, which substantially conforms to the shape of the receptacle. The cover may be constructed of metal, porcelain or other suitable material and has its two corners 70 farthest from its vertical axis provided with openings 15, adapted to register with the openings 7 of the receptacle when the cover is placed over the receptacle.

In use, the manufacturer packs the articles in the receptacle for sale and when purchased by the consumer, the receptacle may be utilized to dispense the articles to the individual user in a sanitary and self-serving manner, without further handling of the articles. To convert the receptacle into a dispenser, the corner portions 80 6, are removed, thereby forming elongated vertical openings 7, through which the upper ends of the articles within the receptacle are caused to extend, by reason of the inclined sides of the bottom 9, which cause the lower ends of the articles 85 through and beyond the openings 7, so they may be easily grasped and removed from the receptacle.

It is to be understood that the form of my invention herewith shown and described is to be taken as a preferred example of the same and that certain changes in the shape, size and arrangement of the parts may be made without departing from the spirit of the invention or the scope of the subjoined claims.

Having thus described my invention, I claim:—

1. A receptacle of the character described comprising a body member of rhombic shape, the corners of said body farthest from its vertical axis having vertical openings formed therein, and an inverted rhombic pyramidal shaped bottom.

2. A receptacle of the character described comprising a body member of rhombic shape, the corners of said body farthest from its vertical axis having vertical openings formed therein, a partition extending between the corners of the

body nearest its vertical axis, and an inverted rhombic pyramidal shaped bottom.

3. A dispensing container for toothpicks and the like comprising a hollow body member of rhombic shape, the acute angles of the body having a removable portion near the top of the body to provide elongated withdrawal openings,

an inverted rhombic pyramidal shaped bottom extending from the lower edges of the sides of the body and a depending skirt surrounding the lower end of the body extending below the apex of the bottom.
